(57) CLAIM

The ornamental design for a triple display clock with AC outlet, as shown and described.

DESCRIPTION

FIG. 1 is a front perspective view of a triple display clock with AC outlet according to my new design;

FIG. 2 is a front view of the design of FIG. 1;

FIG. 3 is a rear view of the design of FIG. 1;

FIG. 4 is a left side view of the design of FIG. 1;

FIG. 5 is a right side view of the design of FIG. 1;

FIG. 6 is a top view of the design of FIG. 1; and,

FIG. 7 is a bottom view of the design of FIG. 1.

The broken lines illustrate environmental structure that form no part of the claimed design.
